DIE-OPERATING MEANS FOR DUPLEX HEAD NAIL MACHINES

Clarence E. Chism, Pittsburg, Calif.

Application June 23, 1953, Serial No. 363,531

3 Claims. (Cl. 10—53)

This invention relates to improved die-operating means for duplex head nail machines.

A duplex head nail has a second head spaced axially from the usual head at the nail end. Such nails commonly are manufactured from wire stock in a machine which includes the usual feed mechanism, wire gripping dies, reciprocable hammer, and cut-off mechanism, and in addition a second set of longitudinally movable gripping dies situated between the first dies and the hammer. The first dies occupy a fixed position longitudinally of the wire, although of course at least one of them moves radially of the wire for alternately gripping and releasing the wire. When both sets of dies are gripping the wire, a single blow of the hammer simultaneously upsets both heads on one nail. The head at the nail end is upset between the hammer and the longitudinally movable dies. The head which is spaced from the end is upset between the two sets of dies. An exemplary machine of this kind is shown in Little et al. Patent No. 2,381,171, dated August 7, 1945, and reference can be made thereto for a more detailed understanding.

These machines include a mechanism which continuously urges the longitudinally movable dies in the exit direction away from the longitudinally fixed dies. An object of the present invention is to provide an improved mechanism for this purpose, that is, a mechanism which has a long life, which is not subject to clogging from nail "whiskers" produced during cutting, and which is easily accessible.

A more specific object is to provide an improved die-operating mechanism which includes depending spring pressed rods that urge the longitudinally movable dies forward against their holders, the mounting being clear of any nail "whiskers" and readily accessible.

In accomplishing these and other objects of the invention, I have provided improved details of structure, a preferred form of which is shown in the accompanying drawings, in which:

Figure 1 is a top plan view of a portion of a duplex head nail machine which has a die-operating mechanism constructed in accordance with my invention;

Figure 2 is a vertical section on line II—II of Figure 1;

Figure 3 is a perspective view of the dies and die holders;

Figure 4 is a horizontal sectional view showing the relation of the dies as they grip the wire stock before the hammer strikes the latter;

Figure 5 is a view similar to Figure 4, but showing the position as the hammer strikes a blow; and

Figure 6 is another view similar to Figure 4, but showing the position after the dies have retracted, the stock has been fed another increment, and the blades have severed a finished nail therefrom.

Figures 1 and 2 show a die block 10 which is adapted to be fixed to the bedplate of a duplex head nail machine. The die block carries a pair of die holders and dies 12 and 12a which occupy a fixed longitudinal position with

2

respect to the wire stock and are shown only diagrammatically, and a second pair of die holders 13 and 13a situated at the exit side of the first pair. As best shown in Figure 3, the faces of the die holders 13 and 13a at their entry side (i. e., the faces directed toward the die holders 12 and 12a) contain grooves 14 and 14a. Dies 15 and 15a are mounted in said grooves and are pivoted to their respective die holders on vertical pins 16 and 16a situated adjacent the outer ends of the dies. Thus the inner ends of the dies 15 and 15a can move longitudinally of the wire. The inner ends of the four dies are notched to grip a wire W from which duplex head nails N are formed. In Figures 4, 5 and 6 the hammer of the machine is indicated diagrammatically at 17 and the cutters 18 at 18.

In accordance with the usual operation of such machines, both sets of dies simultaneously close on the wire W after it has been fed to the proper position (Figure 4). The hammer 17 advances and with a single blow upsets a first head H₁ on the end portion of the wire which protrudes beyond the dies 15 and 15a and a second head H₂ on the portion of the wire between the two sets of dies (Figure 5). During the upsetting operation the dies 15 and 15a pivot rearwardly toward the dies 12 and 12a on their pivot pins 16 and 16a. Next the hammer retracts, and the dies 15 and 15a also pivot forwardly back to their retracted position. The present invention affords a mechanism for retracting these dies, as hereinafter explained. Thereafter both sets of dies release the wire W, which feeds forward one increment (Figure 6). The cutters 18 then cut the finished nail N from the wire and form the point thereon. The sequence just described is repeated for each nail. The feed mechanism and the operating means for the various mechanisms, other than the longitudinally movable dies, are not involved in the present invention, and therefore no showing is made. Nevertheless reference can be made to the aforementioned Little et al. patent for a complete showing of typical mechanisms of this kind and their operating means.

In accordance with the present invention, the upper face of the die block 10 carries a U-shaped yoke 19 rigidly attached thereto (Figures 1 and 2). A fixed horizontal shaft 20 extends between the upstanding arms of said yoke substantially the length of the die block. A pair of approximately horizontal arms 21 and 21a are pivotally mounted on said shaft. A coil spring 22 surrounds the portion of the shaft above the die 15 and has a loop 23 that bears downwardly against the back portion of the arm 21. The outer end of said spring is fixed to a bolt 24 carried by the upstanding arm of the yoke 19. The inner end of said spring is fixed to a bolt 25 carried by the midportion of the shaft 20. A second coil spring 22a is similarly related to the portion of the shaft 20 above the die 15a and the arm 21a.

The die block 10 contains a pair of vertical bores 26 and 26a. The forward portions of the arms 21 and 21a carry depending rods 27 and 27a respectively that extend loosely through these bores and bear against the rearward faces of the dies 15 and 15a. The rearward faces of the die holders 13 and 13a are recessed as indicated at 28 to accommodate said rods. The springs 22 and 22a continuously bear downwardly against the back portions of the arms 21 and 21a and thus urge the rods 27 and 27a and the dies 15 and 15a forwardly toward the retracted position of the latter. These springs are readily yieldable when the hammer 17 strikes to enable the dies to pivot with the hammer blow, but they immediately return the dies to their retracted position when the hammer retracts.

It is seen that my invention places the operating means for the longitudinally movable dies at a location which is easily accessible and also well removed from the cutters

of the machine. The operating means is of simple construction readily installed on existing machines without otherwise altering their structure.

While I have shown and described only a single embodiment of the invention, it is apparent that modifications may arise. Therefore, I do not wish to be limited to the disclosure set forth but only by the scope of the appended claims.

I claim:

1. In a duplex head nail machine which includes a die block, a set of longitudinally fixed dies mounted on said die block for alternately gripping and releasing wire stock, an additional set of die holders mounted in said die block on the exit side of said longitudinally fixed dies, and a set of longitudinally movable dies pivoted to said additional die holders on the side toward said longitudinally fixed dies, the combination therewith of a mechanism urging said longitudinally movable dies to a retracted position away from said longitudinally fixed dies, said mechanism comprising upright support means carried by the upper face of said die block, a shaft mounted on said support means, arms pivoted on said shaft to turn on a horizontal axis, rods depending from each of said arms and bearing against said longitudinally movable dies, and spring means carried by said shaft above said die block 25 and acting on said arms to urge said rods against said longitudinally movable dies, said die block and said additional die holders having vertical passages accommodating said rods.

2. A combination as defined in claim 1 in which the 30

spring means include coil springs surrounding said shaft and having loops in engagement with said arms.

3. In a duplex head nail machine which includes a die block, a set of longitudinally fixed dies mounted in said die block for alternately gripping and releasing wire stock, an additional set of die holders mounted in said die block on the exit side of said longitudinally fixed dies, and a set of longitudinally movable dies pivoted to said additional die holders on the side toward said longitudinally fixed dies, the combination therewith of a mechanism urging said longitudinally movable dies to a retracted position away from said longitudinally fixed dies, said mechanism comprising support means carried on the upper face of said die block and extending thereabove, pivotal mounting means carried by said support means, depending rods supported from said mounting means and bearing against said longitudinally movable dies, and spring means carried by said mounting means above said die block and urging said rods against these dies, said die block and additional die holders having vertical passages accommodating said rods.
